DESIGN.

J. PEGEL.

TABLE COVER OR CURTAIN.

No. 21,002.

Patented Aug. 18, 1891.

UNITED STATES PATENT OFFICE.

JULIUS PEGEL, OF PHILADELPHIA, PENNSYLVANIA, ASSIGNOR TO JOHN BROMLEY & SONS.

DESIGN FOR A TABLE-COVER OR CURTAIN.

SPECIFICATION forming part of Design No. 21,002, dated August 18, 1891.

Application filed January 30, 1891. Serial No. 379,713. Term of patent 3½ years.

To all whom it may concern:

Be it known that I, JULIUS PEGEL, a subject of the Emperor of Germany, residing at Philadelphia, in the county of Philadelphia and State of Pennsylvania, have invented a certain new and original Design for a Table-Cover or Curtain, of which the following is a specification, reference being had therein to the accompanying drawings.

My invention relates to the surface ornamentation of a table-cover or curtain, usually applied to a woven chenille fabric; and it consists of the design therefor illustrated in the accompanying photographic drawing, its leading features being a series of isolated floral figures A A' A², arranged around the edge of

the table-cover or curtain, to constitute in effect a bordering contrasting with a field center B, composed of similar floral figures.

I claim as my invention—

1. The design for a table-cover or curtain, substantially as shown and set forth.
2. The design for the border of a curtain, consisting of the parts A A' A², substantially as shown and set forth.

In testimony whereof I affix my signature in presence of two witnesses.

JULIUS PEGEL.
